UNITED STATES PATENT OFFICE

PERCY E. HUNTER AND LOUIS E. ENDSLEY, OF PITTSBURGH, PENNSYLVANIA; SAID
ENDSLEY ASSIGNOR TO SAID HUNTER

METHOD OF AND APPARATUS FOR SEPARATING METAL SHEETS

Application filed January 16, 1930. Serial No. 421,156.

Our invention relates to a method of and apparatus for loosening or separating the metal sheets of a pack, such as the sheets contained in the piles or stacks of steel sheets in connection with tin plate mill operations, etc.

In tin plate mill operations, the metal sheets are handled in piles or packs, during annealing and other operations, and frequently the sheets of a pack become stuck together so that separation thereof in a convenient manner without injury to the sheets presents a troublesome problem.

One object of our invention is to provide a means and a method by which the sheets of a pack can be rapidly and economically separated or loosened from one another, without pounding or bending operations of such nature as will deform or distort the sheets.

One form of apparatus by which our invention may be practiced is shown in the accompanying drawings wherein Figure 1 is a side elevational view of a machine for operating upon metal packs; Fig. 2 is a cross sectional view thereof taken at right angles to the view of Fig. 1; Fig. 3 is a sectional plan view showing a modification of the structure of Figs. 1 and 2, and Fig. 4 is a diagrammatic view showing still another modification.

This application constitutes a modification of or an improvement upon the disclosure of our application, Serial No. 371,327, filed June 17, 1929.

Referring to Figs. 1 and 2, the apparatus comprises a base or foundation plate 3 that supports a framework 4 which carries the operating parts of the apparatus. A shaft 5 mounted upon the base is driven through a pulley 6 from any suitable source of power and carries worms 7 that mesh with worm gears which are secured to the lower end of shafts 8. These shafts are journaled at their lower ends in the framework 4 and at their upper ends are slidably supported in lateral extensions of a slide 9 whose vertical movements are guided by slideways 10 that are formed in the framework.

Conical rollers 11 have their shafts supported in bearings on the framework 4 and are driven from the shafts 8, through bevel gearing 12. Co-acting conical rollers 13 have

their shafts journaled in the slide 9 and are driven from the shafts 8, by bevel gears 14 and 15, the gears 14 having sliding key connection with the shafts 8 and being journaled in the slide 9, so that when the slide 9 is moved vertically, the gear wheels 14 may travel therewith, and driving connection therefore maintained between the gear wheels 14 and 15.

The gearing 14-15 is of such reduction that the rollers 13 are rotated more rapidly than are the rollers 11, for the reason hereafter explained, and as will be clear from an inspection of Fig. 1. The rollers 13 are likewise shown as of slightly greater diameter than the rollers 11, so that they will have greater peripheral speed than the rollers 11. This difference in peripheral speed as between the rollers 11-13 may be accomplished either by difference in gear reduction or by difference in diameter of the rollers, if the gear reduction be the same for both the upper and the lower rollers, or by a combination of difference in gear reduction and difference in roll diameter.

In order to permit insertion and removal of sheet metal packs between the rollers 11 and 13, and to accommodate the machine to packs of varying thickness, I provide means for raising and lowering the slide 9, such means consisting of a pair of screws 17 that have threaded connection with extensions 18 of the slide 9, and which are journaled in a top plate or bearing plate 19. The upper ends of the screws 17 carry beveled gear wheels 21 that mesh with gear wheels or pinions 22 which are secured to a shaft 23. This shaft is supported in bearings that are mounted upon the plate 19, and is driven by means of a pulley or hand wheel 24 in any convenient manner.

The top plate 19 is connected to the framework 4 at each corner, by means of bolts 25 that are vertically slidable in the framework and which carry springs 26 interposed between the nuts of the bolt and an offset portion of the framework, so that upward thrust upon the plate 19 when the screws 17 are operated to force the rollers 13 into engagement.

with a pack will be cushioned, thus avoiding excessive strain on the apparatus.

Disposed in a plane transverse to the plane of the slide 9, I mount an idling roller slide 28 that is of generally U form, as shown more clearly in Fig. 2, and which carries a shaft 29 at its lower end upon which deflecting rollers 31 are mounted. The legs of the slide 28 partially embrace and are guided by the slide 9, slideways 32 being provided in the slide 9 for guiding the slide 28 in its vertical movements. A cross head 33 is secured to the upper ends of the legs of the slide 28 and have threaded connection with screw shafts 34 which are journaled in the top plate 19 and in a bearing plate 35 which is mounted on said top plate.

The screws 34 have bevel gear connection with a shaft 36 that is mounted in bearings formed on the plate 35 which is driven by a pulley or hand wheel 37.

In operation, the slides carrying the rollers 13 and 31 are elevated to permit insertion of a metal pack 39 whose sheets it is desired to loosen or separate, the center of the pack preferably coinciding with the vertical center line of the machine. The screws 17 will then be actuated to move the rollers 13 into driving engagement with the pack. It will be seen that the rollers 13 and 11 have their axes so inclined that the surfaces thereof which engage the upper and lower sides of the pack will lie in horizontal lines, but the axes of the rollers 11 and 13 can be so positioned that the pack-engaging surfaces thereof will be disposed at angles to a horizontal plane, in order to effect some bending of the pack when passing through these rolls.

While the rollers 13 have been moved down in position to rotate the pack, the shaft 36 is operated to move the slide 28 and its rollers 31 downwardly to somewhat the position shown in Fig. 2, thus deflecting those portions of the pack to either side of the axes of the rollers 11-13. The rotation of the pack by the rolls 11 and 13 will result in the bending thereof by the rolls 31, the portions thus deflected being brought again to a horizontal plane by the rollers 11 and 13. During the rotation of the pack, the rolls 31 may be gradually moved downwardly to effect gradual deflection of a pack to a desired degree. These rolls may be driven, if desired, instead of having merely idling movement. The rollers 31, while of generally tapered form have their surfaces somewhat concave in a direction longitudinally of their axes, so that the pack will have effective continuous contact therewith from the outer edge of the pack to the inner ends of the rolls.

By driving the upper rolls 13 either faster or slower than the lower rollers 11, that is, by giving them a greater or less peripheral rate of speed through faster rotative movement or by reason of their greater diameter

as above-explained, the upper and lower sheets of a pack are caused to slip relative to one another, tending to give the pack a fan-like shape, thus facilitating the separating action of the rolls on the sheets, through supplementing the bending or flexing of the sheets by the various rollers.

The continued deflection of the sheets by the rollers 31 and return of the deflected portions to a horizontal plane between the rollers 11 and 13, results in effectively loosening the sheets from one another, and after a pack has been subjected to the operation above described, the slides 9 and 28 will be elevated to permit removal of the pack and insertion of another pack.

Referring now to Fig. 3, I show a structure whereby greater flexing and bending of the pack and shifting of its center during rolling is effected. In this structure, the rollers 13a which correspond to the rollers 13 of Fig. 1 and through companion rollers (not shown) which correspond to the rollers 11 of Fig. 1, have their axes extending in a direction generally tangent to the normal center of the pack 39, which center is normally at a midpoint between the inner ends of the rollers 31. The driving rollers 13a being non-radial to the said normal center, they tend to shift the pack so that its central portion will be more effectively brought under the influence of the rollers instead of being permitted to rotate on a fixed axis. This arrangement furthermore tends to effect slippage of the sheets upon one another.

In Fig. 4, we have shown rollers 13b and 11b, corresponding to the rollers 13 and 11 respectively of Fig. 1, but these rollers 13b and 11b are relatively offset in the directions of their axes and radially of a pack rotated thereby, so that when passing between two of these rollers, one upper roller 13b will exert a greater driving force on the pack than will its associated roller 11b, while the other roller 13b will exert a less driving force upon the pack than will its corroborating roller 11b. This arrangement not only tends to effect slippage of the sheets relative to one another, but shifts the axis of rotation of the pack so as to bring the central portion thereof into more intimate relation with the rollers than would be the case if the pack were rotated about a fixed axis.

It will be understood that the rollers of Figs. 3 and 4 may be mounted and driven in the same manner as are the rollers of Figs. 1 and 2.

It will also be understood that the rollers 13b and 11b may be directed toward a given center as are the rollers 11 and 13, or that they may have their axes extending tangentially of the normal center of the pack as indicated by the rollers 13a of Fig. 3.

We claim as our invention:

1. Apparatus for operating upon packs of

sheet material, comprising upper and lower driving rollers for rotating a pack in a direction generally parallel to the normal plane thereof, and means for deflecting portions of 5 said pack from its normal plane during traveling movement thereof, one of the said driving rollers having greater peripheral speed than the other rollers.

2. Apparatus for operating upon packs of 10 sheet material, comprising driving rollers for moving a pack in a direction generally parallel to the plane thereof, and means for deflecting portions of said pack from its normal plane during traveling movement thereof, 15 one of the said driving rollers having greater peripheral speed than the other rollers.

3. Apparatus for operating upon packs of 20 sheet material, comprising two pairs of rollers of tapered form, the reduced ends of each pair being located in proximity to the reduced ends of the other pair, the said rollers being positioned to impart rotative movement of a pack of material placed between the rollers of each pair, and means for imparting greater 25 peripheral speed to one roller of each pair than to the other roller thereof.

4. Apparatus for operating upon packs of 30 sheet material, comprising two pairs of rollers of tapered form, the reduced ends of each pair being located in proximity to the reduced ends of the other pair, the said rollers being positioned to impart rotative movement of a pack of material placed between the rollers of each pair, and means for rotating the 35 said rollers, one roller of each pair being axially offset with respect to its associated roller.

5. Apparatus for operating upon packs of 40 sheet material, comprising two pairs of rollers of tapered form, the reduced ends of each pair being located in proximity to the reduced ends of the other pair, the said rollers being positioned to impart rotative movement of a pack of material placed between the rollers of each pair, and means for rotating the 45 said rollers, each pair of rollers being offset radially of their axes with respect to the rollers of the other pair.

6. Apparatus for operating upon packs of 50 sheet material, comprising compressing rollers arranged to rotate a pack about a center perpendicular to and extending through the body of the pack, and means tending to cause rotation of the pack about a different center 55 with such force as to shift said pack axially of said centers during rotative movement thereof.

7. Apparatus for operating upon packs of 60 sheet material, comprising compressing rollers arranged to rotate a pack about a center perpendicular to and extending through the body of the pack, and means for imparting a greater driving force to one side of the pack than to the other side thereof.

8. The method of operating upon a pack

of sheet material, which comprises rotating said pack about axes perpendicular to the plane thereof, compressing the pack during said rotative movement, and simultaneously shifting the pack radially of the said axes. 70

9. The method of operating upon packs of sheet material which comprises rotating a pack about an axis perpendicular to the plane thereof, deflecting portions of said pack into undulatory paths of travel and simultaneously shifting its axis of rotation. 75

10. The method of operating upon a pack of sheet material comprising rotating said pack about an axis extending perpendicularly through the pack, a greater driving force being applied to one side of the pack than the other side thereof, and simultaneously progressively compressing said pack. 80

In testimony whereof we, the said PERCY E. HUNTER and LOUIS E. ENDSLEY, have hereunto set our hands. 85

PERCY E. HUNTER.
LOUIS E. ENDSLEY.
